US0D1106773S

(12) United States Design Patent (10) Patent No.: US D1,106,773 S
(45) Date of Patent: * Dec. 23, 2025

(54) PAD OR COASTER FOR DRINKWARE

(71) Applicant: YETI Coolers, LLC, Austin, TX (US)

(72) Inventors: Dustin R. Bullock, Austin, TX (US);
Alexander Munao, Austin, TX (US)

(73) Assignee: YETI Coolers, LLC, Austin, TX (US)

() Term: 15 Years

(21) Appl. No.: 29/908,570

(22) Filed: Jan. 12, 2024

(51) LOC (15) Cl. 07-09

(52) U.S. Cl.

USPC D7/624.1

(57) CLAIM

The ornamental design for a pad or coaster for drinkware as shown and described.

DESCRIPTION

FIG. 1 is a front top perspective view of a pad or coaster for drinkware showing our new design;

FIG. 2 is a rear bottom perspective view thereof;

FIG. 3 is a top view thereof;

FIG. 4 is a bottom view thereof;

FIG. 5 is a side view thereof;

FIG. 6 is an opposite side view thereof.

FIG. 7 is a front view thereof; and,

FIG. 8 is a rear view thereof.

The unshaded broken line rectangle within the shaded area forms no part of the claimed design.

1 Claim, 6 Drawing Sheets
